TIME ACTUATED MECHANISM

Alvy R. Brassell, Hazlehurst, Miss.

Application May 16, 1933, Serial No. 671,395

4 Claims. (Cl. 116—25)

My invention relates to certain new and useful mechanism for ringing bells, such as school or church bells, for example.

The invention particularly has for an object to provide a mechanism for the purposes stated that can be constructed and operated at low cost, and is especially adapted for use on farms and in small communities (although, of course, it may be used wherever desired).

10 The invention also comprehends a new and improved timer for actuating the various devices employed, the timer itself having adjustable means to time its operation.

Other objects will in part be obvious and in 15 part be pointed out hereinafter.

To the attainment of the aforesaid objects and ends, the invention still further resides in the novel details of construction, combination and arrangement of parts, all of which will be first 20 fully described in the following detailed description, then be particularly pointed out in the appended claims, reference being had to the accompanying drawings, in which:—

Figure 1 is a front view of my invention adapted 25 as a bell ringer.

Figure 2 is a detail elevation of a portion thereof.

Figure 3 is an enlarged detail vertical cross section on approximately the line 3—3 of Figure 1.

30 Figure 4 is a detail vertical section on the line 4—4 of Figure 5.

Figure 5 is a section on the line 5—5 of Figure 4.

Figure 6 is a detail of the timer-holding bar and trigger.

35 Figure 7 is an enlarged vertical section of one of the timers, part of the cylinder being broken away.

In the drawings, in which like numerals and letters of reference indicate like parts in all of 40 the figures it will be seen that upon a suitable frame 87, which carries vertically spaced supports 88, is mounted, in bearings 90, a shaft 89. This shaft at suitable intervals carries ratchets 91 whose collars are secured to the shaft in any suitable way, as by set screws 91x, so that all ratchets 45 turn in unison with one another and with the shaft.

A two-part sheave 92 is mounted on each ratchet's collar to turn thereon. Each sheave 92 50 has a tape-receiving groove 93 whose bottom has a flattened part 94 midway the ends of which is located a tape-anchoring pin 95 over which an end of the tape 96 is looped and secured. The sheave 92 has a series of pin-holes 97 to receive a cross 55 pin 98 that acts to stop the unwinding of the tape

after a predetermined amount has been unwound, depending on the number of revolutions the particular unit must make.

The sheave 92 has a peripheral notch 99 to receive the finger 113 of the sheave-holding arm 5 110 which is pivoted at 110x to the weight lever latch bar 107 and passes through a suitable guide 111. The member 111 is provided with bearing surfaces on which the arm 110 rocks, as indicated in Figure 3.

10 The sheave 92 has a pawl pivot 100 on which a pawl 101 is mounted and pressed into contact with the ratchet 91 by means of a suitable spring 102. A tape stop 103 is secured on the support 88 to cooperate with the pin 98 in holding the sheave 15 from turning after the required length of tape has been unwound.

A weight guide cylinder 104 is securely mounted on the support 88 and guides a weight or motor 105 which has a collar 106 to cooperate with the 20 weight lever latch bar 107. The weight lever latch bar 107 is pivoted at 108 to a bracket 109 and has its free end extended normally to rest in the bracket 114. A spring 112 serves to hold the weight lever latch bar 107 up and the arm 110 25 disengaged from the sheave when the weight lever latch 107 has been released.

Pivoted at 115 is a latch retainer 117, slotted at 116 and connected by a cable 118 with the end of the trigger 143, and with a hook 119. 30

Slidably mounted on a boxing or column 121 is a collar 120 which is held in place by a pin or set screw 122. The column 121 has holes 123 to receive a cross bolt 124 that is secured by a cotter pin 125 to limit the fall of the weight 105. The 35 weight 105 carries adjustable weights, preferably in the form of disks or washers 127, which are held by pin 126, and which constitute the main power weights. The weight 105 also carries auxiliary weight disks 128 to aid in starting up the 40 movement of the shaft 89. The auxiliary weights operate only for a short time and are stopped when they engage the upper end of the column 121.

On the shaft 89 is a wheel 129 which has a 45 ratchet portion 130 with which a gravity pawl 131 cooperates. It also has a crank 137 that is connected by a rod 136 with the crank 135 of the trunnion 133 of the bell yoke. The bell yoke is mounted in a suitable frame 132 and carries the 50 bell 134 which is secured to it at 138. The arrangement is such that as the shaft 89 is turned the bell 134 will be tolled and when the turning action on the shaft stops the parts will be left 55 in position with the bell about vertical, the crank 55

137 off dead center and the shaft held against turning back by the dog 131 and ratchet 130 (see Figure 2).

Mounted on a bar 139 carried by the support 5 88, is a set of trigger released timer-holding bars, all being of substantially the same construction and one less in number than the number of timer units employed. For example, the drawing shows four timer units and three trigger devices. These 10 devices each comprise brackets 141 and 145, a timer-holding bar 142 pivoted at 143 in the bracket 141 and a trigger 143 pivoted at 144 in the bracket 145, there being a trigger stop 145x provided as shown.

15 The cables 118 of the several units are connected directly to the triggers 143. From the triggers 143 cables 147 extend to and connect with the bails 149 of the buckets of the respective timers 148a, 148b, 148c and 148d. The second cable 20 from the left in Figure 1 and each succeeding cable is provided with a hook 119 so that it may be hooked over the corresponding bar 142 to hold from action the buckets of the second and succeeding units until after the bars have been 25 released by the movement of their respective triggers 143 as will later more clearly appear.

As each of the timers is essentially of the same construction, a detailed illustration of one of them only has been given. By reference to Figure 1 30 it will be observed that the cylinder contains a suitable liquid, such as water, and on this liquid normally floats a bucket 52 having a conical bottom 53 to avoid pocketing air beneath the bucket and to insure the proper entry of the water 35 through the valve 54. The conical bottom 53 has an opening over which is secured a suitable valve 54 to admit liquid into the bucket. The valve 54 has a cock 55 by which the rate of flow of liquid into the bucket may be regulated or timed by 40 turning the valve setting lever 56 from one position to another. The lever 56 has an indicator 53 to overlie the dial plate 57 which is suitably graduated. The ends of the dial plate 57 are secured, at 59, rigidly to the wall of the bucket 52 45 in any suitable way.

In order that the bucket may be quickly emptied of its liquid contents when it is raised from the liquid in the cylinder—as when it is desired to reset the bucket—the bucket may be provided with an aperture 60 containing a threaded plug 61 on the end of a stem 62 that projects through a hole in the dial plate 57 and is provided with a handle 63 by means of which the plug may be unscrewed and replaced at will. 50 The dial plate 57 is graduated into suitable time 55 divisions of hours and minutes (not shown) and into quarter-hour intervals. By setting the indicator 53 to any time indication desired the bucket 52 will not draw the cable 147 taut and release the trigger until the time interval set has 60 elapsed. When the indicator 53 is positioned as shown in Figure 1 it is set for a four-hour interval, the maximum for which this particular unit has been designed.

65   *Operation of the bell ringer*

Assume the parts to be set as shown in Figures 1, 2 and 3, and all the buckets of the motor units free of water. The timer 148a is set to operate, 70 say at nine o'clock, timer 148b at 11 o'clock, timer 148c at one o'clock and timer 148d at three o'clock, for example, when timer 148a acts to draw the cable of 147—118 taut it trips the trigger 143 and turns over latch retainer 117, thereby 75 releasing the weight lever latch bar 107 of the first

unit, which in turn releases the weight 105 and moves arm 110 to release the sheave 92 of the first unit (left-hand unit) in Figure 1. This allows weight 105 to fall and toll the bell for the time interval for which pin 124 was set (this may 5 be any time interval found desirable). As soon as the time interval has elapsed weight 105 will be stopped and shaft 89 will stop turning.

When timer 148a released the corresponding trigger 143 it also effected the release of bar 142 10 of the first unit which permitted hook 119 of the second unit to slide off, thereby setting timer 148b ready for action. As soon as the proper time interval has elapsed for timer 148b to operate it, in turn, will move its latch retainer 117 to 15 a position to release the weight lever latch bar 107 of the second unit and thereby free the weight 105 thereof to allow the second ringing of the bell to take place. At the same time that the timer of the second unit releases the retainer 117 20 of its unit, it will also trip the trigger 143 to which its cable 118 is attached and make ready the timer of the third unit, and so on through the series.

It should be understood that there may be as 25 many units employed as may be necessary or desirable for the purpose to be accomplished.

From the foregoing description, taken in connection with the accompanying drawings, it is thought that the construction, operation and advantages of my invention will be clear to those skilled in the art. I wish it to be understood that changes in the details of construction may be made without departing from the spirit of the invention or the scope of the appended claims. 35

What I claim is:

1. A mechanism of the character described comprising a support, a shaft rotatably mounted thereon, a bell, means to ring said bell through rotation of said shaft and a plurality of mechanical motors operatively connected with said shaft 40 to turn the same to cause the ringing of the bell, and means to time the operations of said motors to act at successive intervals.

2. A mechanism of the character described comprising a support, a shaft rotatably mounted 45 thereon, a bell, means to ring said bell through rotation of said shaft, a plurality of motors, means for connecting the same with said shaft to turn the same to cause the ringing of the bell, and means including timers to time the operations of said motors to act at successive intervals, said connecting means comprising individual shaft-rotating elements, one set for each motor, said timing means including means to hold said motors except the first inoperative, and means 55 operated by the timers in succession for releasing the holding means of the next succeeding motor after the preceding motor has ceased to function.

3. A mechanism of the character described 60 comprising a support, a shaft rotatably mounted thereon, a mechanism to be operated by rotation of said shaft, a ratchet fixed to said shaft, a sheave loose on the shaft and having a pawl in cooperation with said ratchet for rotating the 65 shaft in one direction, a back check means for said shaft, a tape wound on said sheave, a weight device connected to said tape for unwinding it and thereby rotating said shaft, a weight lever latch bar for holding said weight static, an arm 70 engaging said sheave to hold it against turning while the weight is held static, a timed device for releasing said weight lever latch bar, and means to free said arm from said sheave when the latch bar is released.

4. A mechanism of the character described comprising a support, a shaft rotatably mounted thereon, a mechanism to be operated by rotation of said shaft, a ratchet fixed to said shaft, a sheave loose on the shaft and having a pawl in cooperation with said ratchet for rotating the shaft in one direction, a back check means for said shaft, a tape wound on said sheave, a weight device connected to said tape for unwinding it and thereby rotating said shaft, a weight lever latch bar for holding said weight static, an arm engaging said sheave to hold it against turning

while the weight is held static, a timed device for releasing said weight lever latch bar, and means to free said arm from said sheave when the latch bar is released, said weight device comprising a weight bar carrying separate weights of two groups, a well in which said bar and weights move down, and means to arrest the weights of one group and functionally free the same from the weight bar after the weights and bar have travelled a predetermined distance. 10

ALVY R. BRASSELL.
